UNITED STATES PATENT OFFICE.

LYMAN H. NELSON, OF PORTLAND, MAINE.

GAME-BOARD.

1,136,552.

Specification of Letters Patent.

Patented Apr. 20, 1915.

Application filed February 8, 1915. Serial No. 6,712.

To all whom it may concern:

Be it known that I, LYMAN H. NELSON, of Portland, in the county of Cumberland and State of Maine, have invented certain new and useful Improvements in Game-Boards, of which the following is a specification.

My invention relates to a game board of the well known type wherein a panel of wood or other suitable material cut away a the corners is inclosed within a rectangular frame, one edge of the frame extending above the panel to form a bank or cushion for the board, the other edge of the frame 15 extending below the panel to form a space to permit the playing pieces to drop through the panel at the corners. In playing the game or games for which this board is adapted, disks or checkers are propelled 20 along the surface of the panel and fall into the openings or pockets at the corners.

The object of my invention is to construct a board of this general type so that it may be made cheaply enough to be sold in the 25 "ten cent trade", so called.

With this end in view I make use of a sheet of pulp board on which is printed the necessary figures to indicate the manner of playing the game, the corners of the sheets 30 being cut away to form pockets. The edges of the sheet rest on strips joined together to form a lower frame and an upper frame coinciding with the lower frame is nailed to the lower frame, securing the edges of 35 the sheet and forming a bank or cushion for playing the game. On the under side of the pulp board sheet and within the space formed by the lower frame is secured an envelop containing the playing pieces, this 40 envelop being of the same thickness as the lower frame and composed of stiff paper rigid enough to support the center of the pulp board sheet to prevent the same from sagging.

My invention may best be understood by means of the accompanying drawing in which is shown a game board constructed according to my invention.

In the drawing, Figure 1 is a plan view, 50 Fig. 2 is a side elevation, Fig. 3 is a central vertical section and Fig. 4 is a perspective view of the envelop for containing the playing pieces.

Referring to the drawings, *a* represents a 55 sheet of pulp board square or rectangular in form, supported on the upper edge of a

lower rectangular frame made up of strips *b* secured together at their ends. The edges of the pulp board sheet are secured to the upper edge of the lower frame by means of an upper frame made up of strips *c* which coincide with the strips *b* of the lower frame. The strips *c* of the upper frame are secured to the strips *b* of the lower frame by nails *d* which pass through the edges of the sheet *a*. 60 The ends of the strips *c* are bent down the thickness of the sheet *a* so that they contact with the upper edge of the lower frame, being securely nailed in place at the ends. The strips *c* thus hold the edges of the sheet 70 firmly in place and they also provide a rim or cushion against which the playing pieces strike.

In forming the two frames the strips *a* are made considerably narrower than the 75 strips *b* because the function of the strips *a* is to form cushion for the playing pieces while the strips *b* are designed to raise the playing portion of the board high enough so that the playing pieces may drop readily 80 through the pockets or openings in the corners.

In the form of the board herein shown a group of six circles *i* are marked or printed in the center of the board. A checker is 85 placed in each circle and the checker or playing piece *h* is snapped with the finger against the other checkers, the game being to force the latter to enter the pocket or corner openings. The game is similar to 90 the game of pool and the lines along the sides mark the space within which the playing piece *h* must be placed for the initial shot.

While I have described one form of game 95 other forms of a similar character may be played on the board.

Sheets of pulp board such as are used in a game board of this character are liable to warp or sag at the center. To offset this 100 tendency, I secure to the under side of the sheet a heavy envelop which answers the purpose of sustaining the center of the sheet and also of containing the checkers or playing pieces.

As herein shown the envelop *g* is made of box shape of heavy paper with a flexible cord *g'* and a button *g''* for fastening. The playing pieces *h* are contained in the box and the latter is glued, cemented or otherwise secured to the under surface of the pulp board sheet.

A game board made as above is capable of being cheaply constructed so that it may be sold in the ten cent trade and at the same time it is substantially put together and will last a long time.

I claim:

1. A game board including a sheet of pulp board having its corners cut away, a lower rectangular frame on which the edges of said sheet rest, an upper rectangular frame resting on the edges of said sheet and coinciding with the lower frame and nails passing through said upper frame and the edges of the sheet and into said lower frame to secure the parts together.
2. A game board including a sheet of pulp board having its corners cut away, a lower rectangular frame on which the edges of said sheet rest, an upper rectangular frame resting on the edges of said sheet and coinciding with the lower frame, nails passing through said upper frame and the edges of the sheet and into the lower frame and an envelop secured to the under surface of the sheet for containing the playing pieces of the game.
3. A game board including a sheet of pulp board having its corners cut away, a

lower rectangular frame on which the edges of said sheet rest, an upper rectangular frame resting on the edges of said sheet and coinciding with the lower frame, and being relatively thinner than said lower frame and nails passing through the upper frame the edges of the sheet and into said lower frame to secure the parts together.

4. A game board including a sheet of pulp board having its corners cut away, a lower rectangular frame on which the edges of said sheet rest, an upper rectangular frame resting on the edges of said sheet and coinciding with the lower frame, nails passing through said upper frame, the edges of the sheet and into the lower frame and an envelop secured to the under surface of said sheet for containing the playing pieces, said envelop being as deep as the lower frame and being composed of material rigid enough to sustain the center of the said sheet.

In testimony whereof I have affixed my signature, in presence of two witnesses.

LYMAN H. NELSON.
